[57] **CLAIM**

The ornamental design for a multi-function lens, as
shown and described.

DESCRIPTION

FIG. 1 is a front elevational view of a multi-function
lens embodying our novel design.

FIG. 2 is a rear elevational view of the same.

FIG. 3 is a top plan view of the same.

FIG. 4 is a bottom plan view of the same.

FIG. 5 is a side elevational view from one side, the
other side being a mirror image thereof.

FIG. 6 is a sectional view on an enlarged scale taken
along the line 6—6 in FIG. 1.

FIG. 7 is a sectional view on an enlarged scale taken
along the line 7—7 in FIG. 1.

FIG. 8 is a fragmentary sectional view on an enlarged
scale taken along the line 8—8 in FIG. 1.

The reflector units are partially shown through the
front wall of the lens in FIG. 1 and on the interior sur-
face of the front wall in FIG. 2 for convenience of
illustration, it being understood that they are uniformly
continuous over the areas on which they are shown.
